ROOFING ELEMENT

Roxton C. McKinnie, Detroit, Mich.

Application February 20, 1939, Serial No. 257,408

3 Claims. (Cl. 108—8)

This invention relates to roofing elements and particularly to composition shingles, such as those made of felt impregnated with asphalt or similar materials.

- 5   An object of the invention is to generally improve roof structures, by the provision of a shingle which adapts itself to the conventional methods of laying, but effects a more economical roof covering.
- 10   Another object of the invention is the provision of an improved shingle which may be readily formed from standard width rolled roofing at a minimum cost and with a loss of little, if any, material.
- 15   Another object of the invention is the provision of a shingle, which may be made with a minimum head lap and with a maximum side lap at the base.
- 20   A further object of the invention is the provision of a shingle which may be laid in such manner as to obtain the benefits of the American Method, while retaining the advantages and economies of the Dutch Lap Method.
- 25   A further object of the invention is the provision of a shingle, which is self-aligning, self-spacing, easy to lay, and one which produces a heavy appearance on the roof.
- 30   Further advantages of the invention will appear as the description proceeds, reference being made to the accompanying drawing, in which:
- 35   Fig. 1 is a fragmentary view with parts broken away, of a roof covered with my improved shingle.
- 40   Fig. 2 is an enlarged fragmentary detail in perspective of a part of the roof illustrated in Fig. 1.
- 45   Fig. 3 is a section taken substantially on the line 3—3 of Fig. 1.
- 50   Fig. 4 is a plan view showing the manner in which two of my improved shingles may be formed from a conventional width of rolled roofing.
- 55   Fig. 5 is a perspective view of one of my improved shingles.

Referring now more particularly to the drawing it will be seen that in the embodiment here disclosed, (Fig. 5) my improved shingle is substantially rectangular in shape, having three straight sides and the fourth side formed in the following manner. The fourth side of my improved shingle is provided with a cut-out 8, an inclined marginal edge 9, and a tab 10. As illustrated in Fig. 4 I prefer to form two of my improved shingles in one operation, by cutting the same from a conventional width of rolled roofing 11. In this instance the rolled roofing is 36 inches wide, from which I cut two shingles, each 12

5   inches wide and having all of the benefits of full rectangular shingles measuring 12 inches by 18 inches. My improved shingles, when cut in this manner, are 12 inches wide and are approximately 21 and $\frac{3}{8}$ inches long on one side and approximately 14 and $\frac{3}{8}$ inches long on the other side. With a shingle formed in this manner I am able to effect certain economies in the manufacture and in the laying as will appear more particularly hereinafter. In some applications I prefer 10 to form the shingle (Fig. 5) with a marker stripe 12, which may take the form of either a depression in the surface of the shingle, a ridge, or merely a line drawn on the face of the shingle. The purpose of the stripe 12 is to give a continuous vertical line to the several courses of shingles after they are assembled into a roof structure as illustrated in Fig. 1. The marker 12 is vertically positioned half way between the cut-out 8 and the opposite end of the shingle. 15

20   In Fig. 1, I illustrate the preferred manner of assembling my improved shingles into a roof structure. In this embodiment 13 represents the roof rafters and 14 the roof sheathing. The shingles are laid horizontally in transverse overlapping courses. In this embodiment the shingle 15 is laid with its straight end 16 disposed towards the left and its long side 17 positioned at the bottom, the marker 12 being disposed in vertical position. The next shingle 18 is laid in the same manner, that is with its straight edge 19 disposed to the left and its long side positioned at the bottom. The left edge 19 of the shingle 18 overlaps the right side 15a of the shingle 15 to the depth of the cut-out portion 8, Figs. 1 and 5. This results in the right end 15a of the shingle 15 being overlapped near the top approximately two inches and at the bottom approximately six inches. The shingle 20 overlaps the right end 18a of the shingle 18 in similar manner. Each succeeding shingle in the same course being similarly applied, until a course of shingles has been disposed across the entire length of the roof. The second course of shingles is applied in the following manner. The shingle 21 is cut along the marker 12 and is laid so that it overlaps the upper edge of the shingle 15 and is arranged so that the marker line 12 is in vertical alignment with the end 16 of shingle 15, and so that its tab 10 extends to the cut-out portion 8 of the shingle 15. In 25 this position the vertical edge of the cut-out portion 8 of the shingle 15 and the end of the tab 10 of the shingle 21 are in vertical alignment, and the horizontal edge of the cut-out 8 of shingle 15 and the upper horizontal edge of the tab 10 of 30

shingle 21 are in horizontal alignment, as is clearly illustrated in Fig. 1. Thus it will be seen that the cut-out portions 8 and the tabs 10 of the respective shingles serve as spacers and 5 means of alignment. The second course of shingles is completed in the same manner. Each shingle is secured to the roof sheathing 14, by nails 22, which are driven through the corners that are ultimately overlapped, namely the upper left 10 hand corner and the lower right hand corner of each shingle. Inasmuch as there is side-lapping of the shingles adjacent the cut-outs 8, the nails 22 driven into the shingles at the upper left hand corners also penetrate and hold the upper right 15 hand corners of the underlying side lapped shingles as at 22a, so that in effect each shingle is nailed at three corners. The fourth and exposed corner of each shingle, except 15, is riveted as at 23, to the next underlying shingle, so that each 20 shingle is secured at all four corners either by nails or a rivet. It will be seen that in this embodiment (Fig. 2) there is a double exposed thickness to the depth of the sidelap at the bottom of each shingle, as at 24. This gives a deep shadow line to the roof. Inasmuch as the markers 12, 25 of the shingles of each course are in alignment with the exposed ends of the shingles in each higher and lower course, I obtain a vertical line effect on the roof structure instead of an oblique line which results when shingles are Dutch lapped, in the usual manner.

In this manner of constructing a roof I am able to obtain the benefits of a six inch side lap at the bottom where there is greater exposure, at 35 the same time providing sufficient side lap at the top, without having to increase the size of the shingle to get the added protection. A roof constructed in this manner has an improved appearance inasmuch as the shingles appear to be smaller because of the effect of the markers 12. In 40 some applications I prefer to provide the individual shingles with different colors on either side of the markers 12, in order to effect a different color scheme on the roof.

45 Having described my invention, what I claim and desire to secure by Letters Patent is:

1. In a shingle having three straight sides and one angular side, the combination of a right angular cut-out portion at one corner adjacent the said angular side, and a laterally extending tab having two sides parallel to the corresponding sides of said cut-out portion, there being a marker element vertically positioned across the face thereof, midway between the vertical edge of the cut-out portion and the straight side of the shingle parallel thereto. 5

2. A roof composed of overlapping courses of shingles, each shingle having one angular side, said angular side having a right angular cut-out portion at the top, and a laterally extending tab at the bottom, said tab having sides parallel to the edges of said cut-out portion, and each shingle having a marker element extending across the full depth of its face, said marker element being arranged in alignment with one of the straight sides of a shingle in each of the courses above and below the course in which it is positioned, said shingles being laid so that each shingle is side-lapped the width of said cut-out portion by a shingle on the same course, and head-lapped approximately twice the depth of said cut-out 20 portion by a shingle in the course next above. 25

3. A roof composed of overlapping courses of shingles, each shingle having one angular side, said angular side having a right angular cut-out portion at the top, and a laterally extending tab at the bottom, said tab having sides parallel to the edges of said cut-out portion, and each shingle having a marker element arranged mid-way between the vertical edge of the cut-out portion and the vertical side of said shingle, said marker being 30 positioned in alignment with one of the straight sides of a shingle in each course above and below the course in which it is positioned, said shingles being laid so that each shingle is side-lapped the width of said cut-out portion by a shingle on the same course, and head-lapped approximately 35 twice the depth of said cut-out portion by a shingle in the course next above. 40
